UNITED STATES PATENT OFFICE.

HARRIET W. KNIGHT, OF NEW YORK, N.Y.

ORNAMENTAL TELEPHONE-CONECING HOOD.

1,340,863.

Specification of Letters Patent. Patented May 18, 1920.

Application filed November 7, 1919. Serial No. 336,519.

To all whom it may concern:

Be it known that I, HARRIET W. KNIGHT, a citizen of the United States of America, residing at New York, in the county and State of New York, have invented certain new and useful Improvements in Ornamental Telephone-Concealing Hoods, of which the following is a full, clear, and exact description.

10 This invention relates to hoods for telephones and has for one of its principal objects to provide an ornamental hood for surrounding and substantially concealing a telephone.

15 Among other objects the invention aims to provide devices of the above mentioned character which are simple and consequently inexpensive from a manufacturing standpoint, and which may readily be attached to or detached from a telephone. Other objects and advantages will appear as the invention is hereinafter disclosed.

Referring to the drawings which illustrate what I now consider preferred forms 25 of my invention:

Figure 1 is a front elevation of one form of my invention.

Fig. 2 is a fragmentary elevation, partly in section, of a part of the structure illustrated in Fig. 1.

Fig. 3 is a view similar to Fig. 1 but illustrating a modification.

Fig. 4 is a fragmentary detail view, partly in section, of a further modification.

35 Fig. 5 is a fragmentary detail elevation illustrating a further modification.

My invention comprises a skirt member and a head member provided with means for so securing them to a telephone that the latter will be surrounded and substantially concealed by the skirt, and the skirt member will be surmounted by the head member. The invention may be embodied in various forms, one of which is shown in Fig. 1 and 45 which may be constructed substantially as follows:

The head member 1 is shown in the form of a doll's head and the skirt member 2 may be secured thereto by gathering the skirt at 3 to grip the neck 4. The device is designed particularly for use in connection with a desk telephone. A telephone of this type

is illustrated in dotted lines and comprises the usual pedestal 5, transmitter 6, mouthpiece 7, receiver hook 8 and receiver 9. 55 Means are provided for supporting said skirt and head on the telephone. Thus I have shown a split ring 10 of heavy cardboard or other suitable material, adapted to encircle the transmitter 6. A block or plug 60 12 adapted to be entered upwardly into and through the neck portion 4 has secured thereto an elastic band 13 which encircles the split ring 10. It will be seen that the ring 10 may be slipped or snapped onto the 65 transmitter and thereby detachably secures the device to the telephone.

When the device is mounted on a telephone, as above described, the latter will be substantially concealed. The skirt 2 may be 70 made wholly or partly of a comparatively stiff fabric such as moiré silk or taffeta so that it will flare outwardly and assume substantially a bell shape or it may be made of softer material to hang as shown in the 75 drawing. In order to insure that the skirt will not cling closely to and reveal the contour of the telephone, means for causing the skirt to flare outwardly in all radial directions may be provided. One form of 80 such means is shown as comprising a hoop or ring 14 secured within and to said skirt. While the voice vibrations might be transmitted through the skirt and into the mouthpiece 7, I prefer to provide the skirt with 85 a slit 15 through which said mouthpiece is adapted to project. By virtue of this construction the device offers no impedance to the transmission of speech. Furthermore in order to facilitate access to the receiver 9 90 the skirt may be slit at 16 and detachable fasteners or snaps 17 may be provided for closing and opening this slit. If desirable a cap 18 on the head may be secured at its ends to the skirt 2 thereby not only increasing the ornamental effect but relieving the skirt against strain where it surrounds the neck 4.

Obviously my invention is susceptible to modification in various respects. Thus the 100 head member 1 instead of being made in the form of a doll's head may assume the form of a block or tubular cap portion 4' about which the skirt 2 is adapted to be

gathered at 3. The block 1' may be provided with an opening 20 for a purpose which will hereinafter appear. The elastic band 13, which is attached to the block 1', and the split ring 10 need no further description. While the ring 10 may be provided with an opening adapted to register with the opening 20 so as to receive the stems of flowers I prefer to place the slit 22 of the transmitter-clamping ring 10 uppermost to receive the stems of the flowers in the following manner: The ring may be spread so as to open the slit and the stems of flowers may be inserted through the opening 20 and the said slit 22. The ring may then be released and the elastic band 13 will cause the former to grip the transmitter.

If desirable a friction member shown in the form of a strip of paper 27 may be secured at one end, between the elastic 10 and block 1', in order to prevent turning of the ring with reference to the block when the ring is spread to receive the stems of the flowers. The slit 22 is thereby prevented from becoming displaced with respect to the opening 20 with which it should register.

Instead of holding the flowers in the manner above indicated a cylindrical plug 25 provided with stem-receiving holes 26 may be inserted in the opening 20 so as to rest on the transmitter 6.

The head member 1, referred to above, need not assume the form in which it consists only of a doll's head but a head member such as that shown in Fig. 5 may be employed. In this form of the invention the head member comprises not only a doll's head 30 but the trunk portion 31 as well. The skirt 2 may be secured to the head member at 3 as described in connection with Fig. 1. With the exception of one additional feature, hereinafter described, the remainder of the device shown in Fig. 5 may be substantially the same as that shown in Fig. 1. In order normally to conceal the mouthpiece 7 a flap of cloth, lace or other suitable material 35 may be sewed or otherwise secured at its upper edge to the skirt 2 so as to hang as indicated in Fig. 5. When it is desired to speak into the transmitter the flap 35 may be raised.

In accordance with the provisions of the patent statutes, I have herein described the principle of operation of my invention, together with the apparatus which I now consider to represent the best embodiments thereof but I desire to have it understood that the apparatus shown is only illustrative and that the invention can be carried out by other means. Also, while it is designed to use the various features and elements in the combination and relations described, some of these may be altered and others omitted and some of the features of each modifica-

tion may be embodied in the others without interfering with the more general results and effects outlined, and the invention extends to such use.

What I claim is:

1. A hood for telephones comprising in combination, a skirt, a head member, and means for supporting said member and skirt on a desk telephone whereby the skirt surrounds the telephone and the head member projects upwardly therefrom. 75

2. An ornamental hood for telephones comprising in combination, a head member, a skirt member secured thereto, and means for securing said members to a desk telephone to cause said skirt substantially to 80 conceal the telephone.

3. A hood for telephones comprising in combination, a skirt, means for causing said skirt to flare outwardly in all radial directions, a head member, and means for supporting said member and skirt on a desk telephone whereby the skirt surrounds and substantially conceals the telephone and the head member projects upwardly therefrom. 85

4. An ornamental hood for telephones comprising in combination, a head member, a skirt member secured thereto and provided with an opening, and means for securing said members to a desk telephone to cause said skirt substantially to conceal the telephone and the telephone mouthpiece to project through said opening. 90

5. An ornamental hood for telephones comprising in combination, a head member, a skirt member secured thereto and provided with an opening, means for causing said skirt to flare outwardly in all radial directions, and means for securing said members to a desk telephone to cause said skirt substantially to conceal the telephone and the telephone mouthpiece to project through said opening. 105

6. An ornamental hood for telephones comprising in combination, a skirt member provided with a mouthpiece-receiving opening and a slit for facilitating access to the telephone receiver, and means for securing said skirt to a telephone substantially to conceal the latter. 110

7. An ornamental hood for telephones comprising in combination, a skirt member provided with a mouthpiece-receiving opening and a slit for facilitating access to the telephone receiver, means for securing said skirt to a telephone substantially to conceal the latter, and means for causing said skirt member to flare outwardly. 120

8. An ornamental hood for telephones comprising in combination, a doll's head, a skirt secured thereto and means for securing said head and skirt to a telephone to cause said skirt substantially to conceal the telephone. 125

9. A hood for telephones comprising in combination, a flower-receiving head member, a skirt member secured thereto and means for securing said head member to a telephone to cause said skirt substantially to conceal the telephone.

10. An ornamental hood for telephones comprising in combination, a head member, a skirt member secured thereto and provided with an opening, means for securing said

members to a desk telephone to cause said skirt substantially to conceal the telephone and the telephone mouthpiece to project through said opening, and a mouthpiece-concealing means secured to one of said members and movable to a position away from the mouthpiece.

In testimony whereof I hereunto affix my signature.

HARRIET W. KNIGHT.
